UNITED STATES PATENT OFFICE.

RICHARD BRAYTON, OF HOMER, NEW YORK, ASSIGNOR OF ONE-THIRD TO
JOSEPH MAPLETHORPE, OF SAME PLACE.

CARRIAGE-TOP PROP.

SPECIFICATION forming part of Letters Patent No. 239,026, dated March 22, 1881.

Application filed January 27, 1881. (No model.)

To all whom it may concern:

Be it known that I, RICHARD BRAYTON, of the town of Homer, in the county of Cortland and State of New York, have invented certain new and useful Improvements in Carriage-Top Props; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

My invention relates to an improvement in adjustable shifting-rail joint-props for carriage-tops.

Figure 1 represents a perspective view of a segment of a seat-frame and side and back rail, showing my invention attached; and Fig. 2 a perspective view of the joint-prop detached.

Referring to the drawings, the letter A indicates the back part of a seat, and B the side thereof.

C indicates the shifting-rail, and D the joint-prop secured to said rail, as will be more fully hereinafter specified.

E indicates the seat-iron, which accomplishes the double purpose of supporting the rail and providing the means of adjusting the joint-prop D.

Heretofore, in the construction of carriage-tops, the joint-prop has been made permanently forged or welded to the side rail. In my improvement this prop is a separate piece detachable from the rail and capable of adjustment by moving it either backward or forward on the rail. Thus, aside from the economy of manufacture, it possesses the advantage over the old style of adaptability to other parts in the trimming and covering of the top, and also in the readjustment for the purpose of tightening the joints when they become loose by wear.

The joint-prop D is provided with an eye, x, through which the rail passes. The eye x

opens through a hollow hub, a, projecting downward therefrom, which hub has screw-threads inside.

The hub a passes through the slot S in the seat-iron E. By means of a set-screw, F, passing through slot S and hub a to rail C, the prop D is firmly secured to the seat-iron E and rail C at any desired point within the scope of the slot S.

It will be observed that the prop D, by reason of the hub a and the set-screw F, may be adjusted laterally in the slot S of the seat-bracket at will, and may, by reason of such adjustability, be made to accommodate different relations and constructions.

Various modifications may be made without departing from the principle or sacrificing the advantages of my invention, the essential feature of which is the adjustability of the prop on the rail in a lateral direction at will by the manipulation of a single screw at each of the rear seat-corners.

Having thus described my invention, what I claim is—

1. In a carriage-top, a rail joint-prop, adapted to be adjusted laterally at will and secured at any desired point by single set-screws, as and for the purpose specified.

2. A seat-bracket, having an elongated slot, combined with an adjustable rail joint-prop, operating in said slot and adapted to be secured at any desired point within the range thereof at will by set-screws, as specified.

3. The combination of the seat-bracket E, having slot S, the prop D, having eye x and hub a, the set-screw F, and rail C, all constructed, arranged, and operating as herein set forth.

In testimony that I claim the foregoing as my own I hereto affix my signature in presence of two witnesses.

RICHARD BRAYTON.
